UNITED STATES PATENT OFFICE.

ADAM MEIRO, OF MOSCOW, RUSSIA.

SPRING-MOTOR.

1,259,262.

Specification of Letters Patent. Patented Mar. 12, 1918.

Application filed December 20, 1916. Serial No. 138,050.

To all whom it may concern:

Be it known that I, ADAM MEIRO, a subject of the Czar of Russia, residing at Moscow, in the Empire of Russia, have invented 5 certain new and useful Improvements in Spring-Motors, of which the following is a specification.

My invention relates to spring motors of the type in which the rotation of the working shaft is effected by the unwinding of 10 wound-up spiral springs, placed in drums geared to the shaft. The main feature of the invention consists in assembling the spring drums on auxiliary shafts in several 15 independent groups, distributed around the working shaft, each of which groups may be moved to or away from this central shaft while the motor is running, to bring in or 20 out of action such a group independently of the others. This affords the possibility of regulating the work of the motor according to the power required and also to wind the 25 separate groups of springs without stopping the motor, which continues to work with the other springs. With the object of 30 attaining the possibility of still more accurate accord in the number of working springs with the required power and also for replacing and winding the damaged 35 separate springs or small sets of springs in each group, the auxiliary shaft of each group is composed of several sections connected together by means of coupling 40 clutches, which make it possible to take out any section of the shaft together with the 45 spring drums mounted on same, leaving the other sections of the same group in place. The section taken out can be placed in a special apparatus, in which the springs are brought up to the required tension, after 50 which operation the section can be put in place in the motor without stopping same.

The number of revolutions of the motor is maintained constant with the aid of a 55 centrifugal regulator acting upon brake devices.

In the annexed drawing showing the motor more or less diagrammatically Figure 1 shows a plan view of the motor with the 60 cover removed; Fig. 2 is a side view of the right hand side, looking in the direction of the arrow in Fig. 1; Fig. 3 is a view of the left hand side of the motor along the line

A—B in Fig. 1; Fig. 4 is a longitudinal section along the line C—D in Fig. 1; Fig. 55 5 is a longitudinal section of the apparatus for winding the springs in the drums of the sections of auxiliary shafts taken off the motor; Fig. 6 is a section of the spring drum and a view of its cover. 60

In the sides of the frame 1 is journaled, in suitable bearings, a centrally arranged power driven shaft 2. In said sides surrounding the shaft bearings are formed a plurality of radially arranged openings 3 65 in each of which is slidably mounted, so as to be moved toward and from the shaft, a bearing plate 4. The corresponding bearing plates of the two opposite sides are connected together by a beam 5, said plates and 70 beam constituting a movable carrier for sectional auxiliary shafts 6 and a driving shaft 7, hereinafter described.

The movement of the bearing plates 4, 75 which are connected in pairs, as above described, is effected by means of cross shafts 8 and screw shafts 9; two screw shafts being provided for each bearing plate and two cross shafts being provided for each pair of plates, but, for the sake of clearness, 80 shafts for only one pair of plates are shown on the drawings. The shafts 8 extend across the frame 1 and carry a worm wheel 8' at each end. The screw shafts 9 are journaled on the sides of the frame on opposite 85 sides of the openings 3 and one end of each screw-shaft engages a threaded ear 4' on the bearing plate 4 and the other end is engaged by one of the worm wheels 8'. Rotary movement is imparted to one of the 90 shafts 8 by means of a hand wheel 10 (Fig. 1) mounted on one of them and simultaneous and uniform movement is imparted to the other shaft by a sprocket chain 10' (Fig. 4) operatively connecting said shafts 95 in a well known manner.

The ends of the shafts 6 and 7 of each group are mounted in corresponding plates 4, in opposite sides of the frame so that the shafts of one group are moved with the 100 plates supporting them.

The shafts 6 are made in sections (one only being so shown in Fig. 1 for the sake of clearness) said sections being connected to short coupling shafts 6' mounted in bearing brackets 11 secured to the beams 5, each

coupling shaft carrying one or more clutches 12, of any suitable type, adapted to connect with a like coupling on the sections 6.

Each shaft section 6 has one or more 5 spring drums 13 (Fig. 6) rotatably mounted thereon, each drum consisting of a cylindrical casing having closed sides and containing a strong helical spring 14 which is fastened at one end to the wall of the drum and 10 at the other end to the shaft section 6 on which the drum is mounted. The periphery of each drum casing is formed with gear teeth 15 by means of which each drum is adapted to mesh with a corresponding gear 15 wheel 16 on the transmission shaft 7.

The springs are wound as hereinafter described and on unwinding rotate the drums which transmit their movement to the gear wheels 16 and shaft 7. On one end of the 20 shaft 7 is fixed a gear wheel 17 adapted to mesh, when moved into position, with a gear wheel 18 fixed on one end of the power shaft 2. On the other end of the shaft 2 is fixed a toothed wheel 19 from which, by 25 means of an arbitrary number of toothed wheels 20, 21, 22, 23, 24, 25, 26, and shafts 27, 28, 29, rotation is transmitted to the main shaft 30, on which a fly-wheel 31 and a fast and loose belt pulley 32 and 33 respectively 30 are mounted.

On the shaft 30 is also fixed a pulley 34 which is connected by a belt 35 with a driving pulley 36 of a centrifugal regulator 37 of ordinary construction, the spindle 38 of 35 which, acting by means of the spring 39, presses a friction disk or block 40 onto a corresponding disk or block on the shaft 27, owing to which fact the speed of the motor is regulated.

40 Each pair of plates 4 supports one transmission shaft 7 and an arbitrary number of auxiliary shafts 6, on which the spring drums 13 are distributed, forming an independent group of devices for transmitting 45 movement to the central shaft 2. In the drawing the front and rear groups each have two shafts 6, and the upper and lower groups each have four such shafts, but these shafts may be provided in any desired number, 50 which may be the same or different for all the groups.

It is obvious that by moving outward a certain group in the openings 3 by means of the transmission mechanism 10, 8, 9, it is 55 possible to uncouple the gear wheel 17 from the gear wheel 18 of the central shaft 2, when it is necessary to wind all of this group of spring drums or reduce the power of the engine to a certain extent. On the contrary, 60 by moving in a group it is put into work. This cutting in and out is effected without any trouble owing to the very small speed of the toothed wheels on the shafts 6, 7, and 2.

In the drawing, the spring drums are divided 65 up into four groups, which can be

brought into or out of action one after the other or simultaneously in any combination. The number of groups may be different, however, on condition that they are arranged concentrically around the shaft 2. 70

All the springs of a disengaged group can be wound simultaneously from outside the motor by means of the following arrangement. On each left hand plate 4 a toothed wheel 41 is rotatively mounted, 75 which wheel is provided with a handle 41' and is in mesh with gear wheels 42 on the corresponding end of the shafts 6. These gear wheels 42 are fixed to ratchets 43, with which pawls 44 can engage. Similar 80 ratchets 43 cooperating with pawls 44 are fastened on the other end of the shafts 6. The shafts 7 are also provided with ratchets 45, with which pawls 46 can engage. These pawls are provided with any suitable lever 85 device by means of which they can be moved into or out of engagement with the ratchets. When it is necessary to wind all the spring of a disengaged group simultaneously, the pawls 46 are moved into engagement with 90 the ratchets 45 on the shaft 7, and the toothed wheel 41 is rotated in the direction corresponding to the winding of the springs. The shafts 6 are thereby brought into rotation, which the pawls 44 do not prevent as 95 they slide freely over the teeth of the ratchets 43, whereas the drums 13 are held in an immovable position owing to the meshing of their teeth 15 with the gears 16 on the now stationary shaft 7, so that the 100 springs are wound up.

When a disengaged group of springs is thus brought into working readiness it is moved in the slots 3 until the toothed wheel 17 meshes with the central wheel 18 and at 105 the moment of such meshing the pawls 46 are lifted. As the shafts 6 are now held stationary by the pawls 44 and the drums 13 can rotate freely, the springs unwind and actuate the motor. 110

Counters 47 of any known construction affording the possibility of regulating the degree of the winding of the springs and indicating their unwinding, are connected in a suitable manner with shafts 6 and 7 of all 115 the groups.

A counter, such as is diagrammatically illustrated in Fig. 5, may consist of a sheave on the shaft 6, connected by a band 6' to a sheave fixed on a worm shaft 6''. The number of revolutions of the latter, which may correspond to the number of revolutions of the shaft 6, is indicated by figures on the counting dial 47 which is moved by the worm shaft in a well known manner. 120

As stated above, each shaft 6 is divided into sections connected together by means of coupling clutches 12. This affords a means, in the case of a spring in one of the sections becoming damaged, to take the section out 125 130

- of the motor and replace the spring with a new one. As the same degree of winding has to be imparted to this new spring as all the other springs of the group from which the section was withdrawn have at the given time, the section is placed in a special apparatus, as shown in Fig. 5 and provided with coupling clutches 12 of the same construction, shaft 7 with gear wheels 16 and counter 47. After the winding of the spring, the drum 13 is connected in some suitable manner with the shaft 6 in order to prevent the unwinding of the spring before the section is put in place. After installing the repaired section between the corresponding clutches 12 of the shaft 6 of the motor and uncoupling of the connection mentioned, the section renews its action, taking part in the work of the whole group.
- Owing to the arrangement of ratchets 43 on both ends of the shafts 6, it is possible to withdraw any desired section of this shaft without interfering with the required immovability of the part of this shaft remaining in the motor.

It will be evident that, while I have shown in the drawing an operative device, still many changes might be made in size, shape and arrangement of parts without departing materially from the spirit of my invention, and I wish, therefore, that the drawing be regarded as in a sense diagrammatic.

What I claim is:

1. A spring motor comprising a driven shaft, a driving shaft, means adapted to operatively connect the shafts, means to move one of said shafts to bring said connecting means into or out of operative connection, and spring actuated means in driving connection with the driving shaft.
  2. A spring motor comprising a driven shaft, a driving shaft, means adapted to operatively connect the shafts, means to move one of said shafts laterally to bring said connecting means into or out of operative connection, and spring actuated means in driving connection with the driving shaft.
  3. A spring motor comprising a driven shaft, a driving shaft, means adapted to operatively connect the shafts, means to move the driving shaft to bring said connecting means into or out of operative connection, and a spring driven member in driving connection with the driving shaft.
  4. A spring motor comprising a driven shaft, a driving shaft, means adapted to operatively connect the shafts, means to move the driving shaft laterally to bring said connecting means into or out of operative connection, and a spring driven member in driving connection with the driving shaft.
  5. A spring motor comprising a centrally arranged driven shaft, a plurality of driving shafts radially disposed about the latter, means adapted to operatively connect
- the driving shafts with the driven shaft, means to move the driving shafts radially to bring the connecting means into or out of operative relation, and spring driven members in driving connection with the driving shafts.
6. A spring motor, comprising a centrally arranged driven shaft, a gear thereon, a plurality of driving shafts radially disposed about the driven shaft, gears on the driving shafts adapted to engage the gear on the driven shaft, spring actuated gears, gears on the driving shafts in mesh with the spring actuated gears, and means to simultaneously move the spring actuated gears and driving shafts to bring the latter into or out of gear with the driven shaft.
7. A spring motor, comprising a driven shaft, a gear thereon, a driving shaft, a gear on the latter in engagement with the aforesaid gear, an auxiliary shaft comprising a plurality of alined sections, means for connecting said sections, spring actuated gears rotatable on said sections, and gears on the driving shaft in mesh with the spring actuated gears.
8. A spring motor, comprising a driven shaft, a gear thereon, a driving shaft, a gear on the latter for engagement with the aforesaid gear, an auxiliary shaft comprising a plurality of alined sections, means for detachably connecting said sections, spring actuated gears rotatable on said sections, gears on the driving shaft in mesh with the spring actuated gears, and means to simultaneously move the auxiliary and driving shafts to bring the gear of the driving shaft into and out of engagement with the gear of the driven shaft.
9. In a spring motor, the combination with a framing, and a driven shaft journaled therein, of bearing plates slidably mounted in the framing toward and from the shaft, a driving shaft and an auxiliary shaft carried by the plates, driving mechanism connecting the auxiliary and driving shaft to rotate the latter, a gear on the driving shaft, a gear on the driven shaft arranged to be engaged by the aforesaid gear, and means to move said plates to bring said gears into or out of mesh.
10. In a spring motor, the combination with a framing, and a driven shaft journaled therein, of a bearing plate slidably mounted in each side of the framing, a rod connecting said plates, a driving shaft journaled in the latter, an auxiliary shaft mounted in the plates and comprising a plurality of alined sections, bearings for said sections carried by the connecting rod, means for detachably connecting said sections, spring actuated gears rotatably mounted on the sections, gears on the driving shaft in mesh with the spring actuated gears, gears on the driving and driven

100

105

110

115

120

125

130

shafts adapted to be brought into engagement, and means to simultaneously move the bearing plates to bring the last named gears into or out of engagement.

5 11. In a spring motor, the combination with a framing, and a driven shaft journaled therein, of bearing plates slidably mounted in the framing toward and from the shaft, a driving shaft and an auxiliary 10 shaft carried by the plates, driving mechanism connecting the auxiliary and driving shafts to rotate the latter, a gear on the driving shaft, a gear on the driven shaft arranged to be engaged by the aforesaid gear, 15 screw-shafts in operative engagement with the plates, and means to actuate the screw shafts to move the plates toward and from the driven shaft.

12. A spring motor comprising a driven 20 shaft, a driving shaft, gears adapted to operatively connect the shafts, a movable carrier for the driving shaft, an auxiliary shaft mounted in said carrier and comprising a plurality of alined shaft sections, 25 means connected with the carrier for supporting the sections, means to detachably connect the latter, a drum rotatably mounted on each shaft section, a coiled spring in each drum connected to the drum and shaft 30 section, means to rotate the sections as a unit independently of the drums to wind up the springs in said drums, and means including the driven shaft to hold the drums stationary during the rotation of 35 the auxiliary shaft.

13. A spring motor, comprising a driven shaft, a driving shaft, gears adapted to operatively connect the shafts, a movable carrier for the driving shaft, an auxiliary 40 shaft mounted in said carrier and comprising a plurality of alined shaft sections, means connected with the carrier for supporting the sections, means to detachably connect the latter, a drum rotatably mounted on each shaft section, a coiled spring in 45 each drum connected to the drum and shaft section, means to rotate the sections as a

unit independently of the drums to wind up the springs in said drums, gears on the latter in engagement with gears on the 50 driving shaft, and pawl and ratchet mechanism for holding the latter stationary during the winding of the springs.

14. A spring motor comprising a driven 55 shaft, a driving shaft, gears adapted to operatively connect the shafts, a movable carrier for the driving shaft, an auxiliary shaft mounted in said carrier and comprising a plurality of alined shaft sections, 60 means connected with the carrier for supporting the sections, means to detachably connect the latter, a drum rotatably mounted on each shaft section, a coiled spring in each drum connected to the drum and shaft section, means to rotate the sections as a unit independently of the drums to wind up the springs in said drums, gears on the latter in engagement with 65 gears on the driving shaft, pawl and ratchet mechanism for holding the latter stationary during the winding of the springs, and a pawl and ratchet mechanism to prevent 70 rotation of the auxiliary shaft in one direction.

15. In a spring motor, a driving shaft, a 75 driven shaft, means adapted to operatively connect the shaft, spring actuated means in driving connection with the driving shaft, means to move the latter into or out of operative connection with the driven shaft, a main shaft, intermediate shafts for transmitting motion from the driven shaft to the main shaft, and a centrifugal regulator operatively connected with the main shaft and adapted to automatically exert 80 a braking action on one of said intermediate shafts.

In witness whereof I have hereunto set my hand in presence of two witnesses.

ENGINEER ADAM MEIRO.
